BY
Geo. P. Kimmel
ATTORNEY.

UNITED STATES PATENT OFFICE.

JOHN WILLIAM WESTWICK, SR., OF GALENA, ILLINOIS.

FURNACE.

Application filed April 18, 1927. Serial No. 184,648.

This invention relates to warm air furnaces and has for its object to provide, in a manner as hereinafter set forth, means for conveniently and expeditiously shaking 5 down the furnace when occasion requires.

A further object of the invention is to provide, in a manner as hereinafter set forth, a warm air furnace provided with a shaking mechanism capable of being operated from 10 one side of the ash pit or at the front thereof.

A further object of the invention is to provide, in a manner as hereinafter set forth, a shaking device for the purpose referred to including a lever operated reciprocatingly connecting bar and an extended ash pit associated with the shaking device, and with the bar of said device disposed transversely of and projecting from one side of the extension of the pit and detachably connected 15 to the operating lever for the device, and further with said side providing a guide and bearing for the bar when reciprocated by the lever.

A further object of the invention is to 25 provide, in a manner as hereinafter set forth, a furnace including an extended ash pit and a slip-on front and with the sides and top of the extension of the pit provided with means to constitute an abutment for said 30 slip-on front, when the latter is mounted in position, to prevent the front from shifting forwardly with respect to the extension of the pit.

A further object of the invention is to 35 provide, in a manner as hereinafter set forth, a furnace provided with an extended ash pit and further with a shaking means or device arranged within the pit and further with an upstanding lever arranged 40 in spaced relation with respect to one side of the pit and connected with said shaking means for operating the latter when required.

Further objects of the invention are to 45 provide, in a manner as hereinafter set forth a shaking means for a furnace or for other purposes for which it is adaptable, which is simple in its construction and arrangement, strong, durable, compact, thoroughly 50 efficient in its use, operated from its side or at its front, readily installed within the furnace and comparatively inexpensive to set up.

With the foregoing and other objects in view the invention consists of the novel construction, combination and arrangement of parts as hereinafter more specifically de-

scribed, and illustrated in the accompanying drawings wherein is shown an embodiment of the invention, but it is to be understood that changes, variations and modifications 60 can be resorted to which fall within the scope of the claim hereunto appended.

In the drawings wherein like reference characters denote corresponding parts throughout the several views:

Figure 1 is fragmentary view, in front elevation illustrating the slip-on front, extended ash pit and shaking means in accordance with this invention and with the ash pit door removed.

Figure 2 is a sectional plan illustrating the grate bars, shaking means, slip-on front, extended ash pit, ash pit door and operating lever for the shaking means, the outer shell being removed.

Figure 3 is a section on line 3—3 Figure 2.

Figure 4 is a fragmentary view in side elevation of the furnace.

Figure 5 is a detail in vertical section.

As is well known, warm air furnaces include outer and inner shells arranged in spaced relation to provide an air heating chamber surrounding the inner shell. The air heating chamber is provided with cool air supply means and warm air outlet means. 80 In the embodiment of the invention forming the subject matter of this application, the outer shell is indicated at 1, the air heating chamber at 2 and the inner shell at 3 and with the latter extended above the means, 85 hereinafter referred to provide the ash pit of the furnace. The inner shell 3 is formed with an opening 3' for the reception of a water pan.

In the embodiment of the invention as disclosed in the application the shell 1 has the lower portion of its front cut away and which is closed by a slip-on front section 4, provided with an opening 5 which registers with the opening 3'. The water pan 100 is not shown.

The furnace includes a base member 6 of angle shaped cross section forming a vertically disposed flange 7. The outer shell 1 is seated on a base member 6 and overlaps the flange 7. The base member 6 at its front is provided with a pair of inwardly extending portions 8, 9 which merge into a plate 10, which is disposed centrally with respect to the base member 6 and projects inwardly and outwardly with respect to the inturned portions 8, 9 of the

base member 6. The plate 10 has a rounded inner end and a squared forward end. That part of the plate 10 arranged outwardly with respect to the inturned portions 8, 9 is of greater width than that portion of the plate 10 which extends inwardly from said portions. That part of the plate 10 which extends inwardly from said portions 8, 9 is of materially greater length 5 than the part of the plate 10 which projects outwardly from said portions. The plate 10 is formed with an upstanding flange 11 which extends from that part of the flange 7 formed on the portion 8 to 10 that part of the flange 7 formed on the portion 9. The flange 11 from one end to the other end thereof is continuous and forms the upper face of the plate 10 with a seat 12. The plate 10 has its upper face, 15 in proximity to its outer end, formed with a transversely extending abutment 13.

Mounted on the seat 12 and extending beyond the portions 8, 9 of the base member 6 is an upstanding casting 14 formed 20 with an open front and having its top, at the outer portion thereof, closed by a flat bridge piece 15 which forms the bottom wall of the opening 3'. The width of the bridge piece 15 is less than half the length 25 of the casting 14 and the latter is arranged below the inner shell 3 see Figure 3. The casting 14 from the rear edge of the bridge piece 15 to the rear end thereof is open.

The ash pit 16 is formed by the plate 30 10 and casting 14 and the latter provides the rear wall 17 and side walls 18, 19 of the ash pit. The plate 10 provides the bottom of the ash pit. The ash pit door is indicated at 20 and is hinged as at 21 to 35 the side wall 19 of the ash pit 16. The door 20 and side wall 18 of the ash pit are provided with coacting means, as indicated at 22 for latching the door 20 in abutting relation with respect to the outer edge of 40 the bridge piece or member 15 and the outer edges of the walls 18, 19. The door 20 when closed is positioned against the abutment 13 and said door 20 is provided throughout with an inwardly extending 45 flange or rim 23 which positions the body of the door a substantial distance from the casting 14, as the flange or rim 23, when the door is closed abuts against the casting. The construction and arrangement of the 50 casting 14, in connection with the door 20, provides an ash pit 16 which is extended from the front 4 of the furnace, see Figure 3. The body of the door 20 is formed with a pair of openings 24 for a purpose to be 55 presently referred to and which are normally closed by the pivoted closures 25.

The walls 18, 19 of the fire box and the bridge piece 15 are flanged on the outer faces thereof and the flange is indicated at 60 26 and extends from the lower end of the

wall 18 to the lower end of the wall 19 and across the bridge piece 15 and provides an abutment. The flange 26 is positioned forwardly with respect to the flange 7 of the base member 6 and provides an abutment 70 for the slip-on front 4. The slip-on front 4 is formed with an opening for the purpose of straddling the casting 14 forwardly of the flange 7 and surrounding such opening is a flange 27 which abuts against the flange, shoulder or abutment 26 and the latter provides means for positioning the slip-on front, as well as to prevent it shifting forwardly with respect to the casting 14. The slip-on front 4 seats on top of the casting 80 14 and abuts against the sides thereof. The slip-on front 4 at the sides thereof is formed with rearwardly extending inclined portions 28, which abut the flange 7 and have their lower ends notched as at 29 for the purpose of overlapping upstanding lugs 30 formed on the base member 6, and said lugs 29 act to position the slip-on front 4 and further act to prevent the bottom of 85 said slip-on front 4, at the sides thereof, from shifting forwardly and rearwardly with respect to the casting 14.

Integral with and arranged within the casing 14 at the upper portion thereof and directly below the inner shell 3 is a grate 90 comprising a body portion 31 in which is journaled oscillatory grate bars 32, 33, 34 and 35 and each of which is provided with spaced projections 36 of any suitable contour. The grate bars at their forward ends project a substantial distance from the body portion 31 and are mounted in, as well as extending forwardly from, a hanger 37, which is supported from the bridge piece 15 as indicated at 38. The hanger 37 is formed 100 with notches at the ends thereof through which extend holdfast devices provided by bolts 38 for supporting the hanger from the bridge piece 15. The holdfast devices extend through the bridge piece, see Figure 105 3. The grate bars 33, 34 project a greater distance forwardly of the hanger 37 than the bars 32 and 35. The body portion 31 is provided with spaced projections 39 which oppose the projections 36 on the grate bars 110 32, 35.

Forwardly of the hanger 37, the grate bars 32, 33, 34 and 35 have secured thereto gears 40, 41, 42 and 43 respectively. The gear 40 meshes with the gear 41. The gear 42 meshes with the gear 43, and they are offset with respect to gears 40, 41. The grate bar 33, forwardly of the gear 41, has fixed thereto a collar 44 provided with an L-shaped crank arm 45 and the grate bar 34, forwardly of the gear 42, is provided with a removable collar 46 formed with an L-shaped crank arm 47. The horizontal portion of each crank arm has its inner end connected to the collar whereby the up- 115 120 125 130

standing portion of the crank arm will be offset with respect to the collar. Positioned rearwardly of the upstanding portions of the crank arms, as well as being pivotally connected therewith as at 48, is a connecting bar 49, which is disposed at right angles to the grate bars and extends through an opening 50 formed in the side walls 19 of the ash pit near the top of the latter. The connecting bar 49 projects a substantial distance from the wall 19 and is detachably connected, at its outer end, as at 51, to an operating lever 52 therefor. The lever 52 is pivotally supported at its lower end, as 10 at 53 and is provided at its upper end with a handle 54 which is offset with respect to the pivot 51, the latter forming the connection between the outer end of the connecting bar 49 and the lever 52. The pivot 20 51 is positioned between the transverse median of the lever 52 and the upper end thereof.

When the lever 52 is oscillated, the connecting bar 49 is reciprocated, and the crank arms will impart an oscillatory movement to the grate bars 33, 34 carrying the cog gears 41, 42 therewith and which in turn will oscillate the cog gears 40, 43 imparting a like motion to the grate bars 32, 35. 30 During the oscillation of the grate bars the grate bars 32, 35 will move in an opposite direction with respect to the direction of movement of the grate bars 33, 34, under such conditions the grate surface is agitated

and the ashes allowed to fall into the ash pit. 35

The forward end of each of the grate bars 33, 34 are of triangular contour, as indicated at 55, for the reception of a crank handle for the purpose of oscillating the grate bars from the front of the ash pit 40 when the connecting bar 49 is disconnected from the lever 42 or when one desires to oscillate the grate bars in lieu of employing the lever 52. The crank handle, not shown is inserted through one of the openings 45 45 formed in the door body of the door of the ash pit.

What I claim is:

In a furnace means to provide a forwardly extending ash pit, a plurality of 50 spaced pairs of intermeshing gears arranged in said means, each pair for connection with and for operating a pair of grate bars in opposite directions, a shiftable crank arm within said means for each pair of gears, 55 a connecting bar pivotally attached to said arms for simultaneously operating them, said bar extending through and projecting outwardly from one side of said means, and an upstanding oscillatory lever pivotally 60 connected at its lower end and further pivotally connected intermediate its ends to the outer end of said bar for the purpose of reciprocating it to provide for the shifting of said crank arm simultaneously. 65

In testimony whereof, I affix my signature hereto.

JOHN WILLIAM WESTWICK, SR.
